UNITED STATES PATENT OFFICE.

SMITH C. BERGH, OF SCAPPOOSE, OREGON.

BURGLARPROOF WINDOW LOCK.

Application filed January 16, 1923. Serial No. 612,950.

To all whom it may concern:

Be it known that I, SMITH C. BERGH, a citizen of the United States, residing at Scappoose, in the county of Columbia and 5 the State of Oregon, have invented a new, and useful Burglarproof Window Lock, of which the following is a specification.

My invention is intended for attachment to the window sash for residences, places of 10 business and elsewhere, wherein a device is required for easy attachment to the window, and is so arranged that the window sash may be set at any desired position, and the same cannot be changed without first having 15 released the lock. The lock may be attached to a window already in place in an easy manner, can be made in a number of sizes, can be adapted for attachment on any kind of a sash, and any one can operate the same, 20 as it is of simple construction, and will not easily get out of operating condition, the same may be used in conjunction with a winding using sash weights or it may be installed independently of the sash weight, 25 there being ample support in the lock to support the sash in any desired position.

I attain these objects by the mechanism illustrated in the accompanying drawings, in which—

30 Fig. 1 is a window frame of the usual type, and having the two sash window of the kind adapted to vertical adjustment, in this view are shown two of my window locks secured to the lower sash, though on window sashes of the smaller sizes it is possible 35 to require but one of my locks. Fig. 2 is an enlarged detached view of the lock with the cover plate removed to better illustrate the construction of my lock and the operation 40 of the same, in this view the lock is shown in operative position with the stop pawls in engagement with the window frame. Fig. 3 is a front view of the detached lock having the closure plate also removed, but showing the lock in inoperative 45 position, when the lock is in this position, the window sash may be readily raised, lowered, or adjusted, but when the lever clamps are released, the lock at once positions 50 the sash in a locked position, in which position it remains until the levers are compressed as shown in Fig. 3 thereby releasing the pawls from engagement with the window frame member. Fig. 4 is an enlarged 55 view of the lock in place upon the window sash and in locked position, with the closure

plate on and the lock complete. Fig. 5 is a cross section view of the lock as shown in Fig. 3 and is taken on line B B, this view clearly shows the inner construction of my 60 lock. Fig. 6 is a section view taken on line A and is made to illustrate the method of holding the lever in place about the journal and is made with the closure plate on.

Similar letters and numerals refer to similar parts throughout the several views.

1 is the window frame, and 2 is the lower sash of the vertical adjustable type, 3 is the base of my lock to which the other attachments composing the lock are attached and to which the screws or other attachments are made fast to hold the lock on the window sash. 4 is a pawl like member journaled about pin 5 which passes through the base and the closure plate and forms a rigid journal to support the pawl 4 when an extra exertion would be made upon the sash to force the same open. Passing through the inner end of the pawl member 4 is a pin 6 about which the link 7 is journaled on its one end, it being journaled about the other on pin 8 which is held in place in lever 9. Lever 9 is pivoted about journal 10 which also passes through or into the base 3 and the closure plate 14. To hold the pawl member in the normal or operative position a small pressure spring 11 is positioned between the base member and the closure plate about pin 12, the spring engaging the shoulder like portion 13 of the pawl 4. The members thus far described are for the purpose of preventing the raising of the sash when in locked position but it is apparent that a similar series of members in the opposite position will be required if the window sash is to be locked in position to prevent the lowering of the sash. This is accomplished as shown by pawl member 15 being journaled about pin 16 and the pin 17 engaging the member 15 and the link 18 100 being journaled at the other end to receive pin 19 which in turn is attached to lever 20 which is pivoted about pin 21 which is secured to the base 3 and the closure plate 14. The spring 11 engages and contacts 105 with the pawl 15 upon the shoulder 13^a.

Having thus described my invention in such detail that any one skilled in the art may make the same, I wish to make the following claims therefor:

1. In combination, a casing open at opposite sides and adapted to be secured to the

inner face of a window sash with one open side facing the side of the window frame, a pair of substantially triangular pawl members positioned in the casing with a side adjacent and substantially parallel to a horizontal end of said casing, said pawls each having an angle opposite said side pivoted to the casing, the pivots being in vertical alinement and adjacent each, the angle of each pawl adjacent the window frame being sharp to engage the material of said frame, a pair of links each pivoted to the remaining angle of a respective pawl, a pair of T-shaped levers each having a stem projecting from the open side remote from the frame and having its arms pivoted respectively to the casing and one of the links, and spring means urging the sharp angles of said pawls toward the window frame and the stems of the levers apart.

2. In combination, a casing open at opposite sides and adapted to be secured to the inner face of a window sash with one open side facing the side of the window frame, a pair of substantially triangular pawl members positioned in the casing with a side adjacent and substantially parallel to the horizontal ends of said casing, said pawls

each having an angle opposite said side pivoted to the casing, the pivots being in vertical alinement and adjacent each, the angle of each pawl adjacent the window frame being sharp to engage the material of said frame, a pair of links each pivoted to the remaining angle of a respective pawl, a pair of T-shaped levers each having a stem projecting from the open side remote from the frame and having its arms pivoted respectively to the casing and one of the links, a rib closing the central part of the open side between the lever stems and constituting a limit stop for the movement of said levers toward each other, a post adjacent said rib, a V-shaped spring having its apex held between said post and rib and its arms constantly tending to move apart, and shoulders on the pawls against which said arms engage to force the pawls into engagement with the window frame.

In testimony that I claim the foregoing as my own I hereunto attach my signature in the presence of two witnesses.

SMITH C. BERGH.
